(57) **CLAIM**

The ornamental design for an ice cream vending machine as shown.

DESCRIPTION

FIG. 1 is a top front left side isometric view of an ice cream vending machine showing our new design;

FIG. 2 is a front view thereof;

FIG. 3 is rear view thereof;

FIG. 4 is a right-side view thereof;

FIG. 5 is a left-side view thereof;

FIG. 6 is a top plan view thereof; and,

FIG. 7 is a bottom plan view thereof.

The broken line portion of the figure drawings is included to show portions of the article that form no part of the claimed design.
